New York, N. Y., a corporation of New York

Application May 9, 1952, Serial No. 286,918

13 Claims. (Cl. 118—226)

1

This invention relates to a device for feeding and coating articles and more particularly to a mechanism for feeding insulator cards having terminals thereon and for oiling the projecting ends of terminals of the cards as they are fed.

An object of the present invention is to provide an effective and efficient device for feeding articles.

A further object of the invention is to provide a device of simple construction for applying a coating to surfaces of the articles as they are fed.

In accordance with one embodiment of the invention as applied to an apparatus for processing cards having terminals thereon, there is provided a magazine for guiding a stack of cards and a mechanism for supporting the stack of cards in the magazine and successively releasing the bottom card therefrom onto a pivoted transfer member which swings the card into a predetermined position where the ends of the terminals are gripped between a pair of oil impregnated pads on a second pivoted transfer member, which in turn moves the card into engagement with a holder on the card processing apparatus. The second transfer member is moved from the holder in the plane of the card to cause the card to be disengaged from the second transfer member and to cause a film of oil to be wiped onto the ends of the terminals as they are withdrawn from between the oil pads.

Other objects and advantages of the invention will become apparent by reference to the following detailed description thereof and the accompanying drawings illustrating a preferred embodiment of the invention, in which

Fig. 1 is a plan view of the device for feeding and oiling cards shown as applied to a portion of the card processing apparatus;

Fig. 2 is a plan view of a card with terminals thereon which is to be fed and oiled in the present device;

Fig. 3 is an enlarged sectional view of the card taken on the line 3—3 of Fig. 2;

Fig. 4 is a side elevational view of a portion of the mechanism as shown in Fig. 1;

Fig. 5 is a vertical longitudinal cross-sectional view of the device taken on the line 5—5 of Fig. 1;

Fig. 6 is an enlarged vertical longitudinal sectional detailed view of a portion of the card supporting and releasing mechanism shown in Fig. 1 with parts thereon shown in changed position;

Fig. 7 is a plan sectional view taken on the line 7—7 of Fig. 5;

Fig. 8 is a plan sectional view of a portion of the device taken on the line 8—8 of Fig. 4;

2

Fig. 9 is a vertical sectional view taken on the line 9—9 of Fig. 4;

Fig. 10 is a fragmentary vertical sectional view taken on the line 10—10 of Fig. 4; and

Fig. 11 is an enlarged sectional view through a portion of the second transfer member in its lower position showing a card therein being transferred onto a card holder of the card processing apparatus.

10 Referring to the drawings (Figs. 1, 2, and 5), the device is adapted to release the lowermost one of a stack of cards 15 arranged in a magazine 16 and deposit it onto the guide pins 18 on a holder 19 mounted on a rotatable feed table or carrier 20 of an apparatus for attaching the cards and terminals to conductor wires for fabrication into telephone equipment. The carrier 20 is intermittently indexed to advance successive holders 19 into position to receive the cards. The cards 15 (Figs. 2 and 3) comprise an arcuate strip of phenol fiber insulation 25 provided with a pair of aligning apertures 26 and having a plurality of terminal members 28 secured thereto. The ends 29 of the terminals 28 extend from one side edge of the card and are adapted to be engaged by a wiper contact of the telephone apparatus into which the cards are finally assembled and the other ends of the terminals project from the other edge of the card and are provided with upwardly extending flanges 30—30 providing a U-shaped sleeve forming portion 31 adapted to be attached to insulation covered wires of the telephone apparatus.

35 The magazine 16 comprises a pair of corner posts or bars 35 vertically recessed at 36 to receive the ends of the cards 15 therein and a pair of rods 38—38 disposed to engage the rear edge of the cards 15 between a pair of adjacent terminals 28. The lower end of the posts 35 are secured to irregularly shaped frame plates or brackets 40 fixed to a frame member 42 (Figs. 1, 4, and 5). The member 42 is supported on a stationary plate 44 disposed above the rotatable feed table 20. Brackets or straps 47 fixed to the posts 45 35 serve to support the rods 38.

The cards 15 arranged in a stack are supported in spaced relation to each other by the flanges 30 of the sleeve portions 31 of the terminals 28 and when arranged in the magazine 16 the stack of cards 15 is supported on lower movable supporting elements 55, 56, 57 and 58 or upper movable frame elements 65, 66, 67 and 68 (Figs. 1, 5, 6, and 7). The upper supporting elements are slidably mounted on the lower elements and the upper and lower ones are mounted for recip-

recable movement in opposite directions to release successive cards from the lower end of the stack. The supporting elements 55 and 65 are in the form of narrow fingers adapted to fit between the ends 29 of the central pair of terminal members on the cards 15 and are formed as projections on plates 70 and 71, respectively. The plates 70 and 71 (Figs. 5, 6, 7, and 10) are mounted for sliding movement relative to each other in an aperture 72 in the lower end of a bar 73 and the ends of the plates 70 and 71 are guided for sliding horizontal movement in guide slots 75-75 in the bar 73. The bar 73 is secured to cross members 76-76 which in turn are secured to the post 35. The lower and upper supporting members 56 and 66 (Figs. 1, 6, 7, and 9) are wide enough to engage a plurality of terminals 28 and are secured to plates 80, 81, respectively. The lower and upper supporting members 57, 58, 67, and 68 are adapted to engage and support the endmost terminals 28 on the cards 15 and are likewise secured to the slide plates 80 and 81, respectively. The ends of the slide plates 80 and 81 are guided for horizontal movement in guideways 83-83 (Figs. 7 and 9) formed in side frame members 85 and 86 secured to and supported from the lower end of the posts 35.

A mechanism is provided for reciprocating the card supporting members which comprises a rock shaft 90 journaled in the frame members 85 and 86 and having a double crank arm 91 fixed thereto to the opposite ends of which are connected links 92 and 93 which are pivotally connected to the slide plates 80 and 81. Another rock shaft 95 also journaled in the frames 85 and 86 has a double crank arm 96 secured thereto and to the opposite ends of which are pivotally connected links 97 and 98 which in turn are pivotally connected to the plates 70 and 71. The rock shafts 90 and 95 are connected together for simultaneous oscillation in opposite directions by arms 101 and 102 connected to the ends of the shafts 90 and 95, respectively, and interconnected by a link 103. The arm 101 is formed integral with the lever arm 105 which is pivotally connected to one end of a piston rod 106 of a piston 107 which is reciprocable within a cylinder 108. The cylinder 108 which has air lines 109 and 110 connected thereto to admit air under pressure to actuate the piston and the card release mechanism in opposite directions is pivotally connected at its upper end 112 to a frame member 113 fixed to the post 35 at one end and at its other end connected by a bar 114 to the frame member 85. Thus, in response to the actuation of the piston 107 the lower plates 70 and 80 and the upper plates 71 and 81 are caused to reciprocate to alternately advance and retract the card supporting member 55 relative to the members 56, 57, and 58 and the member 65 relative to the members 66, 67, and 68, and the upper and lower members relative to each other successively to cause the lowermost one of the stack of cards to be released.

As successive cards from the stack are released they fall upon a transfer plate 120 (Figs. 5, 7, and 9) which has a pair of tapered aligning or retaining pins 121 engageable in the apertures 26 in the card. The plate 120 is roughly V-shaped and has a pair of apertured bearing members 122 freely mounted on the rock shaft 90 for supporting the plate 120 for free oscillation about the shaft. On a laterally extending portion 123 of the plate 120 a double crank arm 124 is fixed to one end of which is pivotally con-

nected a piston rod 125 (Fig. 5) on a piston 126 which is reciprocable within a cylinder 127. The cylinder 127 has pipe lines 128 and 129 connected thereto for admitting actuating fluid therein and is pivotally connected at its upper end 130 to a frame member 134. The frame member 134 is secured at one end to the post 35 and is supported by a member 135 connected at its lower end to the frame member 86. Pivotally connected at 133 to the other arm of the double crank arm 124 is the lower end of a yoke or bifurcated link 139 which has a cross arm 140 (Figs. 5 and 9) at its upper end. The cross arm 140 is connected to a piston 143 of a dashpot 145 disposed between the spaced arms of the bifurcated yoke 139. A member 146 of the dashpot has a pair of opposed recesses for receiving pivot mounting pins 148-148 which extend through slots 149 in the arms of the yoke 139 and are secured in the spaced arm portions 150 of a loop formed in the frame member 134 for receiving the yoke 139 and the dashpot 145 therein.

In response to the actuation of the piston 126 the transfer plate 120 is caused to move from a substantially horizontal position directly below the stack of cards (Fig. 5) to a substantially vertical position (Fig. 4) to transfer the card 15 onto a second transfer arm and oiling device 153 at an angular position intermediate the horizontal and substantially vertical positions. The dashpot 145 which is of the hydraulic type controls the downward movement of the transfer plate 120 and the card thereon to effect a relatively slow movement from the horizontal position to the intermediate position to permit the card to be transferred to and gripped by the second transfer and oiling device 153 and then to permit a rapid or free movement of the transfer plate 120 to its substantially vertical position.

The second transfer device 153 comprises a plate 188 pivotally connected at 189 to the forked lower end of a supporting plate 199. A portion 191 of the plate 188 extends beyond the pivot 189 and is pivotally connected at 192 to a piston rod 193 of a piston 194 movable in a cylinder 195, which in turn is pivotally connected at its upper end 196 to a lug 197 fixed to the supporting plate 190. A pair of pipe lines 198 and 199 direct the flow of compressed air to the opposite ends of the cylinder to effect reciprocation of the piston and the oscillation of the plate 188 about the pivot 189. At its forward end the plate 188 is bifurcated and has pivotally connected thereto at 201 a movable jaw 202, a part of which is substantially circular. The movable jaw 202 has a lug 203 thereon which is pivotally connected to the piston rod 204 of a piston 205 reciprocable in a cylinder 206 which in turn is pivotally connected to a lug 208 on the plate 188. Pipe lines 210 and 211 connected to the cylinder 206 direct the fluid into the cylinder for reciprocating the piston 205 and oscillating the movable jaw 202 to and from open and closed positions. A set screw 212 limits the movement of the jaw 202 in one direction to its closed position.

The bifurcated divergent ends 213 of the plate 188 (Fig. 8) are provided with guide recesses 214 for receiving and positioning the ends of a card 15 on the transfer member 153. The ends of the card 15 are supported on end portions 215 of a plate 216 fixed to the lower side of the plate 188 at one end thereof. Between the ends 215, the plate 216 is cut away to provide clearance for the movement of the end of the

transfer plate 120. Felt pads 220 and 221 having convex peripheries conforming substantial to the inner curvature of the cards 25 are secured to the plate 216 and the jaw 202, respectively. The jaw 202 is provided with a groove 223 in the convex edge portion through a substantial portion of the arcuate periphery thereof and a plurality of holes 224 establish communication between the groove 223 and the felt pad 221. Oil from a stationary oil supply pipe 226 (Fig. 5) drops at a controlled rate into the groove 223 and is distributed through the holes 224 to the felt pad 221, and when the jaw is closed some of the oil from the pad 221 is transferred to the pad 220 to maintain the pads supplied with oil.

When a card 15 is moved by the plate 120 from the magazine to the intermediate or dotted line position as shown in Fig. 5, the end portions 29 of the terminals on the card are disposed above and in engagement with the pad 220, and the jaw 202 is actuated to its closed position to grip the ends 29 of the terminals between the oil pads 220 and 221 to securely hold the card 15 as the transfer plate 120 continues its movement to a substantially vertical position. Air admitted through the line 199 to the cylinder 195 causes the plate 188 to be oscillated to its lower position (Fig. 4) to move the card 15 onto the card holder 19 of the feed table 20 with the aligning pins 18 in engagement with the apertures 26 in the card. The plate 188 is then moved horizontally to the left as viewed in Fig. 4 to disengage the card 15 from between the oiling and gripping pads 220 and 221 by means comprising a cylinder 230 (Figs. 1, 4, and 5) to one end of which the supporting plate 190 is secured.

The cylinder 230 is mounted for sliding movement in a guideway 231 formed in the frame member 42 and has a bore or cylinder chamber 232 for receiving a piston 233 therein. The piston 233 has a piston rod 234 secured to a stationary lug 235 on the frame 42 to secure the piston against movement. Pipe lines 237 and 238 (Fig. 4) direct fluid from an air line 239 under control of a solenoid valve 240 to opposite ends of the cylinder 230 to cause a movement of the cylinder relative to the fixed piston, the stroke of the cylinder being arrested in one direction by the engagement of the piston with a rubber bumper 241 and in the opposite direction by the engagement of a stop screw 242 on the cylinder with a stationary member 243. The solenoid valve 240 is actuated under control of a switch 245 which in turn is actuated by a cam 246 on a cam shaft 247 rotated in timed relation to the indexing of the carrier 20. Other cams on the cam shaft 247 actuate switches similar to the switch 246 to control solenoid valves connected to the pipe lines from the other fluid actuators for actuating the components of the above-described device in a predetermined sequence.

For each cycle of operation the lowermost card 15 of the stack in the magazine 16 is released onto the transfer plate 120 which positions the ends 29 of the terminals of the card in engagement with the pad 220 at which time the movable jaw closes to grip the ends 29 between the oil pads 220 and 221 and hold the card on the second transfer device 153 as the first transfer plate 130 continues its movement, after which the second transfer device 153 is moved to its lower position to place the card onto the pins 18 of the holder 19 on the feed table 20 and is then moved horizontally to the left to disengage the transfer device 153 from the card and wipe a

film of oil on the ends 29 of the terminals and permit the feed table 20 to be indexed to position another holder 19 in alignment with the feeding device. The device 153 is then raised and advanced to its normal position as shown in Fig. 5 and the first transfer plate 120 and the card ejecting the mechanism are returned to their normal positions preparatory to the feeding of another card.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. In an apparatus of the class described, means for supporting a card having terminals with the end portions of the terminals projecting beyond the card, a pair of jaws having oil impregnated pads thereon engageable with the ends of said terminals, and means for actuating said jaws to grip the ends of the terminals and to move the jaws away from said terminals to cause a film of oil to be wiped onto the ends of the terminals.

2. In a device for feeding cards and oiling the projecting ends of terminals mounted thereon, the combination of means for supporting one of said cards against movement relative to said means in one direction, a pair of oil dispensing elements engageable with the ends of said terminals for depositing oil thereon, means for moving said supporting means to a predetermined position to support said card in a position to be engaged by said elements, means for moving the elements towards each other to yieldably clamp the ends of the terminals therebetween, and means for effecting relative movement between said elements and said card supporting means while said elements are engaging said terminals to cause oil to be deposited on said terminals.

3. In an apparatus of the class described, the combination of an article holder, a transfer element movable from a first position remote from said holder to a second position adjacent said holder for receiving an article at said first position and carrying it into engagement with said holder at said second position, means for feeding articles to said first position, a gripper element on said transfer element to grip a portion of the article therebetween, a member adapted to be impregnated with oil on one of said elements engageable with said article, means for actuating said gripper element, means for actuating said transfer element, and means for moving said transfer element in a direction to cause the article to be withdrawn from between said elements and to cause a film of oil to be deposited on a portion of said article.

4. A device for feeding cards onto holders on a feed table and for oiling the ends of terminals on the cards comprising a magazine for holding a supply of said cards with terminals thereon, a pair of jaws having oil impregnated pads thereon arranged to grip the ends of the terminals on said cards, means for feeding successive cards from said magazine into said jaws, and means for moving said jaws through a predetermined path to deposit said card onto a holder on said feed table and to withdraw the jaws from said card to cause a film of oil to be deposited on said terminals.

5. A device for feeding cards onto holders on

a carrier and for oiling the ends of terminals on the cards as they are being fed comprising a magazine for holding a supply of said cards, a pair of jaws having oil impregnated elements thereon arranged to grip the ends of said terminals on said cards, means for feeding successive cards from said magazine into said jaws, means for moving said jaws to closed position to grip the terminals therebetween, means for moving said jaws and the card therebetween to position said card on a holder on said carrier, and means for withdrawing the jaws from said card while said jaws are closed to cause a film of oil to be deposited on said terminals.

6. In an apparatus of the class described, the combination of an article holder, a transfer element movable from a first position remote from said holder to a second position adjacent said holder for receiving an article at said first position and carrying it into engagement with said holder, means for feeding successive articles to said first position, a gripper element on said transfer element to grip a portion of the article therebetween, a member on one of said elements impregnated with oil and engageable with said article, means for actuating said gripper element, means for actuating said transfer element, and means for effecting relative movement between said transfer element and said article holder in a direction to cause the article to be withdrawn from between said elements and to cause a film of oil to be deposited on a portion of said article.

7. A device for feeding cards onto successive card holders at a loading station comprising a magazine for holding a stack of cards, means for supporting said stack of cards in said magazine and for releasing the bottom card therefrom, a first transfer member movable to and from the bottom of said magazine for receiving the card released therefrom and moving said card through a predetermined path, a second transfer member having a jaw portion movable through a predetermined path from a first position in the path of movement of a card on said first transfer member to a second position adjacent a holder at said loading station, a jaw member mounted for movement on said second transfer member and cooperable with said jaw portion thereof to grip a card therebetween, means for actuating said card releasing means and said first transfer member to release said card onto the first transfer member and move the card through said path into engagement with the jaw portion of said second transfer member, means for actuating said jaw member from a normally open position to a closed position for yieldably gripping said card therebetween, means for actuating said second transfer member from said first position to said second position to move said card into engagement with said holder, and means for moving said second transfer member laterally relative to said holder to cause the withdrawal of the card from said jaws.

8. A device for feeding cards onto successive card holders at a loading station comprising a magazine for holding a stack of cards, means for releasing the bottom card from said magazine, a first transfer member mounted for pivotal movement to and from the bottom of said magazine for receiving the card released therefrom and moving said card through an arcuate path, a second transfer member mounted for pivotal movement and having a jaw portion movable through an arcuate path from a first position in the path of movement of a card on said first transfer

member to a second position adjacent a holder at said loading station, a jaw member pivotally mounted on said second transfer member and cooperable with said jaw portion thereof to grip a card therebetween, means for actuating said card releasing means to release a card onto the first transfer member, means for actuating said first transfer member to move the card through said path into engagement with the jaw portion of said second transfer member, means for actuating said jaw member to yieldably grip said card therebetween, means for actuating said second transfer member from said first position to said second position to carry said card into engagement with said holder, and means to effect a relative lateral movement between said holder and said second transfer member to withdraw the card from between said jaws.

9. A device for feeding cards onto successive card holders at a loading station and oiling the projecting ends of terminals on the cards comprising a magazine for holding a stack of said cards, means for supporting said stack of cards in said magazine and for releasing the bottom card therefrom, a first transfer member movable through a predetermined path to and from the bottom of said magazine and the stack of cards therein for receiving the card released therefrom and moving said card through a predetermined path, a second transfer member having a first oil dispensing element thereon movable through a predetermined path into and from a first position in the path of movement of a card on said first transfer member and a second position adjacent a holder at said loading station, a second oil dispensing element on said second transfer member cooperable with said first element to grip the ends of the terminals on the card therebetween, means for actuating said card releasing means to release a card onto the first transfer member, means for actuating said first transfer member to move the terminals on the card into engagement with said first element on said second transfer member, means for actuating said second element into engagement with said first element for yieldably gripping the ends of the terminals therebetween, means for actuating said second transfer member from said first position to said second position to carry said card into engagement with said holder, and means for moving said second transfer member from said holder in a direction substantially parallel to a face of the card to cause the ends of the terminals to be withdrawn from said elements and oil to be deposited on said terminals.

10. A device for feeding cards onto card holders at a loading station and oiling the projecting ends of terminals on the cards comprising a magazine for holding a stack of cards, means for releasing the bottom card from said stack, a first transfer member mounted for pivotal movement to and from the bottom of said magazine and a predetermined transfer position for receiving the card released from said magazine and moving said card to said transfer position, a second transfer member having a first oil dispensing element thereon and mounted for pivotal movement to and from a first position in engagement with a card at said transfer position and a second position adjacent a holder at said loading station, a second oil dispensing element mounted for movement on said second transfer member and cooperable with said first element to grip the ends of the terminals on the card therebetween, means for actuating said card releasing

means to release a card onto the first transfer member, means for actuating said first transfer member to move the card to said transfer position with the terminals on the card in engagement with said first element on said second transfer member, means for actuating said second element into engagement with said first element for yieldably gripping the ends of the terminals therebetween, and means for actuating said second transfer member from said first position to said second position to carry said card into engagement with said holder and for moving said second transfer member from said holder to withdraw the elements from engagement with the ends of the terminals to effect the deposit of oil on said terminals.

11. A device for feeding cards onto card holders at a loading station and oiling the projecting ends of terminals on the cards comprising a magazine for holding a stack of cards, means for releasing the bottom card from said magazine, a first transfer member mounted for pivotal movement through an arcuate path to and from an upper position adjacent the bottom of said magazine for receiving a card released from the magazine and moving said card to a transfer position intermediate the upper and lower position of said transfer member, a second transfer member mounted for pivotal movement and having a first oil impregnated element thereon movable to and from a first position in the path of movement and a lower position remote from said magazine of a card on said first transfer member and a second position adjacent a holder at said loading station, a second oil impregnated element mounted for movement on said second transfer member and cooperable with said first element to grip the ends of the terminals of a card at said transfer position, a fluid operated actuator for actuating said card releasing means to release a card onto the first transfer member, a fluid operated actuator for actuating said first transfer member to move the card thereon into said transfer position with the terminals on the card in engagement with said first element on said second transfer member, dashpot means for controlling the speed of said transfer member from said upper position to said transfer position, a fluid operated actuator for actuating said second element into engagement with said first element for yieldably gripping the ends of the terminals therebetween, a fluid operated actuator for actuating said second transfer member from said first position to said second position to carry said card into engagement with said holder, a fluid operated actuator for moving said second transfer member from said holder in a direction substantially in a plane of the card to withdraw the oil impregnated elements from the terminals and cause a film of oil to be wiped on said terminals, and means for coordinating the movements of said fluid operated actuators.

12. A device for feeding articles onto holders on

a carrier comprising a magazine for holding a stack of articles, means for releasing the bottom article from said magazine, a first transfer member mounted for pivotal movement through an arcuate path to and from an upper position adjacent the bottom of said magazine and a lower position remote from said magazine for receiving an article released from the magazine and moving said article to a transfer position intermediate the upper and lower position of said transfer member, a second transfer member mounted for pivotal movement and having a gripping element thereon movable to and from a first position in engagement with an article at said transfer position and a second position adjacent a holder on said carrier, a second gripping element mounted for movement on said second transfer member and cooperable with said first element to grip an article at said transfer position, a fluid operated actuator for actuating said releasing means to release an article onto the first transfer member, a fluid operated actuator for actuating said first transfer member to move the article thereon into said transfer position, dashpot means for controlling the speed of said transfer member from said upper position to said transfer position, a fluid operated actuator for actuating said second element to yieldably grip the article therebetween, a fluid operated actuator for actuating said second transfer member from said first position to said second position to carry said article into engagement with said holder, a fluid operated actuator for moving said second transfer member from said holder to withdraw the gripping elements from the article, and means for coordinating the movements of said fluid operated actuators.

13. In a device for feeding cards and oiling the projecting ends of terminals mounted thereon, the combination of means for supporting one of said cards and for holding said card against movement in one direction relative to said means, a pair of oil dispensing elements engageable with the ends of said terminals for depositing oil thereon, means for moving said supporting means and the card thereon to a predetermined position with the terminals in engagement with one of said elements, means for moving the other element into engagement with said one element to yieldably clamp the ends of the terminals therebetween, and means for effecting relative movement between the elements and the card supporting means in said one direction while said elements are engaging said terminals to cause oil to be deposited on the terminals.
